BED HEADBOARD

Alfred Rabb, Jr., 422 Clermont Ave., Brooklyn, N.Y.

Filed Dec. 13, 1960, Ser. No. 63,217

Term of patent 14 years

(Cl. D5—4)

FIGURE 1 is a front perspective view of the bed headboard showing my design with the terminal door members and one upper drawer thereof in partially open position;

The back of the article is conventionally plain.

I claim:

The ornamental design for a bed headboard, as shown and described.
